CLAIM

The ornamental design for a rotating camera, as shown and described.

DESCRIPTION

FIG. 1 is a front perspective view of a rotating camera, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view thereof shown in a state of use; and,

FIG. 10 is a front perspective view thereof shown in a state of use.

The broken lines in the drawings illustrate the portions of the rotating camera, which form no part of the claimed design. The rotating camera is shown with symbolic breaks, formed by dash-dot-dash broken lines.

The appearance of any portion of the article between the break lines forms no part of the claimed design.
